N. S. DICKINSON

ELEVATOR SEQUENCE SAFETY DEVICE

Filed June 18, 1920

Neville S. Dickenson Inventor

By his Attorney

Emerson R. Newell

UNITED STATES PATENT OFFICE.

NEVILLE S. DICKINSON, OF GLEN RIDGE, NEW JERSEY, ASSIGNOR TO ELEVATOR SUPPLIES COMPANY, INC., A CORPORATION OF NEW YORK.

ELEVATOR SEQUENCE SAFETY DEVICE.

Application filed June 18, 1920. Serial No. 390,048.

To all whom it may concern:

Be it known that I, NEVILLE S. DICKINSON, a citizen of the United States, residing at Glen Ridge, N. J., have invented certain new and useful Improvements in Elevator Sequence Safety Devices, of which the following is a clear, full, and exact description.

My invention relates to elevator safety appliances, and particularly to appliances suitable for electrically controlled elevators, and the invention has for its object the provision of a suitable arrangement for controlling elevators of this character, which is simple in construction, reliable in action, and which may be readily installed without making any changes in the mechanical construction in the systems to which it may be applied.

A feature of my invention relates to the provision of means whereby it will be impossible to start the elevator unless a certain sequence of manipulation of control is followed, such sequence being first the closing and latching of all elevator gates or hatchway doors, and afterwards the manipulation of an elevator starting mechanism, controller or starting switch.

A further feature relates to the provision of means, whereby not only is the elevator prevented from moving unless this order of manipulation is followed, but also whereby the elevator is prevented from moving under control of the starting switch or mechanism if this is manipulated prior to the closing of the elevator gates even though said gate or gates are subsequently closed, and until the starting switch or mechanism is again moved to neutral position.

Another feature of the invention relates to the manner of connecting up my improved safety appliance to elevator systems already installed by merely making suitable changes in the electrical connections.

Other objects and important features of the invention will become apparent from the following detailed description and claims when considered in connection with the accompanying drawing, in which I have shown my invention in diagrammatic form.

Referring to the drawings, 1 indicates an elevator starting mechanism, which may be in the form of the usual controlling lever, which when swung to one position causes the elevator to move upwardly, and when swung

to the opposite position causes the elevator to move downwardly.

In the constructions now in common use, the starting switch 1 is designed to control the closing of a suitable circuit which will energize a switch magnet, indicated at 7 in the drawings, which magnet may be arbitrarily considered as the "up" magnet. Said switch may also close a suitable circuit through a switch magnet 17, which may be considered the "down" magnet.

The manner in which the circuit through either "up" magnet or "down" magnet is controlled forms an important feature of my present invention and will be described in detail. In order, however, to make it clear how my improved safety appliance operates in conjunction with the usual elevator controlling devices, I will describe the usual arrangement of circuits whereby the elevator is controlled to move up or to move down, depending upon whether the magnet 7 or the magnet 17 is energized. If it be assumed that the magnet 7 has been energized, and that the contacts 4 and 13 are moved downwardly to closed position, then the current will pass from the point 2, connected to a main feed wire A, to the contact 3, contact 4, contact 5, to the point 6. From 6 the current will pass along the wires 8 and 9 to the motor. Returning from the motor along the wire 10, the current will flow through the wire 11 to contact 12, through contact 13 to contact 14, through wire 15 and wire 16 to a point 18 connected to a second main feed wire B on the opposite side of the line. The motor will then be energized and will operate to move the elevator up. It is, of course, understood that brake magnets are provided and acceleration magnets, but these and their circuits have not been shown for the reason that such showing would unduly complicate the drawing, and furthermore these devices are usually found in modern elevator equipments and form no part of my present invention.

If it be assumed that the starting device 1 has been moved to the opposite position from that previously assumed, and if it also be assumed that the magnet 17 has been energized thereby closing the switches 23 and 27, then the current will flow as follows:

Starting at 2, to the point 19, said current will then flow through the wire 20, wire 21

to the contact 22, through switch 23, wire 24, to the point 25, where it is connected to the wire 11, through which it flows to the wire 10 and to the opposite side of the motor, returning from the motor by the wire 9 to flow through the wire 8 to the point 6, whence it flows to the contact 26 through switch 27 to contact 28, through wire 29 to the wire 16, to the point 18 on the other side of the line. The motor will be energized and rotate in the opposite direction, causing the elevator to move downwardly.

In the above description of the circuits, it has been assumed that the magnet 7 or the magnet 17 was energized. It is one of the features of my invention to prevent energization of these magnets even through the switch 1 is manipulated, if such manipulation is prior to the closing of the gate or hatchway contacts, such preventing means remaining effective until the switch 1 is again moved to neutral position. The circuit including the wires 9 and 10 leading to the motor may for convenience be designated the elevator operating circuit, because when this circuit is supplied with current, it is possible to move the elevator up or down.

In order to thus control the energization of the magnets 7 and 17, I provide a gate circuit which includes a gate contact 30 and a gate contact 31 connected in series; and while I have shown two gate contacts, as many more may be provided as desired. Said gate circuit also includes means for controlling a circuit including the "up" or "down" line switch magnets 7 and 17, said controlling means preferably being in the form of a relay magnet 32 and a relay magnet 33 connected in series with said gate contacts. When the gate contacts are closed, therefore, current will pass from the main feed wire A, beginning at the point W, through the wire 34, wire 35, contact 36, switch 37, contact 38, wire 39, through the relay 33 to wire 41, through the gate contacts to wire 42 and through the relay 32 to wire 43 and to the other side of the line at the point V, a suitable fuse 44 being interposed in the line. The switch 37 is normally closed so that upon closing of the gate contacts current will flow through the gate circuit and both relays 32 and 33 will become energized. The core 45 of the relay 32 is connected to a bell-crank lever 46, pivoted at 47, the other arm of said lever carrying switches 48, 49 and 50. The lower relay has a core 45¹ connected to an arm of a bell crank 46¹ pivoted at 47¹, said bell crank carrying switches 51, 52 and 53. When the gate circuit is closed and both relay magnets 32 and 33 are energized, the switches 48 and 50 close a circuit, which may include the "up" magnet 7 or the "down" magnet 17, depending upon whether

the switch 1 is thrown to the left or to the right. The circuit thus formed may be conveniently designated as the line circuit or control circuit because when it is closed, it then becomes possible for the elevator operating circuit to be closed to cause the elevator to move up or down, according to the position of the switch 1. The switch 1 is connected by a wire 54 to the main feed wire A, and when said switch is thrown to the left it closes a contact at 55, completing a control circuit including the magnet 7 and the switches 48 and 51, said circuit running as follows: from the main feed wire A, through the wire 54, switch 55, magnet 7, to the point Z. From the point Z through the wire 56, wire 57 to the point 58, from this point to the contact 59, through the switch 51 to the contact 60, wire 61 to the contact 62, through the switch 48 to contact 63, to wire 64 and through wire 43 to the other side of the line. The "up" magnet then becomes energized and closes the switches 4 and 13, and the elevator motor is operated in the usual manner already described. Under these conditions, with the gate contacts closed, if the switch 1 is thrown to the right closing the contact 65, current will pass from the main feed wire A through the wire 54, contact 65 and magnet 17 to the point Z, whence it will flow as already described to the other side of the line. It will thus be seen that the elevator operating circuit, which is closed by either line switch magnet 7 or line switch magnet 17, depends upon the closing of the control circuit through one or the other of said line switch magnets. Said control circuit, on the other hand, is closed by the relay means included in the gate circuit. The gate circuit must, therefore, be closed before it is possible to obtain any current through either magnet 7 or 17.

With the arrangement of circuits and controls thus far described, it would be possible to first close the control circuit by the elevator starting switch and afterwards close the gate contacts, and current would then be supplied to the control circuit and the elevator circuit would then be closed.

In order, however, to require the closing of the gate contacts prior to the closing of the starting switch, I provide means whereby the starting switch is rendered ineffective to close the control or line switch circuit through either magnet 7 or 17, unless the gate contacts are first closed. In order to do this, I provide a separate circuit, which for convenience I designate the "break circuit": and I provide means in this circuit for breaking the gate circuit, said means preferably consisting of magnetic means in the form of a relay magnet 66 and a second similar magnet 67. These magnets have a common core 68, which when either

magnet is energized causes the switch 37 to move away from the contacts 36 and 38, thereby breaking the gate circuit. If the gate contacts, or any one of them, are open and the switch 1 is moved to close the contact at 55, then no current will pass through the line switch magnet 7, because the circuit including said magnet is broken at the switches 48 and 51. However, with the 10 parts so positioned, the break circuit is completed as follows:

From the contact 55 to the point X, through a wire 69 to wire 70, wire 71 to contact 72, through switch 53 to contact 73, 15 wire 74 to contact 75, switch 50 to contact 76, wire 77, wire 78 to relay 67, through said relay to wire 79, wire 80, resistance 81 to the point W on the other side of the line. Energization of relay 67 will result in opening the switch 37, which will cause a break 20 in the gate circuit so that even if all of the gate contacts are then closed, the relay magnets 32 and 33 will receive no current and the control circuit will not be completed. The 25 only way in which the elevator can be started, under the conditions just described, is by moving the elevator switch to a position to break contact at 55, thereby breaking the circuit through the relay 67, allowing 30 the switch 37 to again complete the gate circuit. Relays 32 and 33 will then be energized, and switches 48 and 51 closed.

If the elevator starting mechanism 1 is moved to the right to close the contact 55, 35 a circuit from the feed wire A will pass to the point Y, through wires 82, 83 and 84 to contact 85, switch 52, contact 86, wire 60 to contact 88, through switch 49 to contact 89, to wire 90, to relay 66, from which it will 40 flow through the wire 91 to the wire 80, and from there to the other side of the line.

With any one or more of the gate contacts open, the break circuit is always closed at the switches 49 and 50 and 52—53. When, however, the gate circuit is closed, thereby energizing relays 32 and 33, the switches 49, 50, 45 52 and 53, are opened and the switches 48 and 51 closed.

An emergency switch 92 may be provided 50 if desired, the purpose of this being to close a circuit around the relays 32 and 33 in case it is desired to move the elevator with one or more of the gates open, as may sometimes be necessary in an emergency.

In order to install my improved safety 55 control appliance, it is only necessary to locate the points V, W, X, Y and Z and make the proper electrical connections at these points. Since these points are usually designated on a panel board, they are very easy to connect up with. My improvement, therefore, lends itself to ready installation.

From the above description, it will be noted that grounding of the switch contact 60 30 with the line wire B, for instance, would

result in preventing any flow of current through the relay 32. Current, however, flowing through the relay 33 would be ineffective to close the control circuit, which would still remain broken at the switch 48. 70 Similar grounding of the contact 31 with the line wire A would cut out the relay 33 and no current would be supplied to the control circuit.

While I have shown a preferred form of 75 my invention, it is obvious that variations may be resorted to within the spirit thereof and that parts of my improvement may be used without others.

Having thus described my invention, what 80 I claim and desire to secure by Letters Patent is:

1. In an elevator safety appliance, the combination with an elevator operating circuit and an elevator starting mechanism 85 controlling said circuit, of a gate circuit including gate contacts, means in said gate circuit actuated on closing thereof for permitting closing of said operating circuit by said elevator starting mechanism, and means 90 for breaking said gate circuit if said elevator starting mechanism is manipulated prior to closing of said gate contacts.

2. In an elevator safety appliance, the combination with an elevator operating circuit and an elevator starting mechanism controlling said circuit, of a gate circuit including gate contacts electromagnetic relay means in said gate circuit actuated on closing thereof for permitting closing of said operating circuit by said elevator starting mechanism, and means for breaking said gate circuit if said elevator starting mechanism is manipulated prior to closing of said 105 gate contacts.

3. In an elevator safety appliance, the combination with an elevator operating circuit and an elevator starting mechanism controlling said circuit, of a gate circuit including gate contacts, means in said gate circuit actuated on closing thereof for permitting closing of said operating circuit by said elevator starting mechanism, and a break relay for opening said gate circuit if said elevator starting mechanism is manipulated 110 prior to the closing of said gate contacts.

4. In an elevator safety appliance, the combination with an elevator operating circuit and an elevator starting mechanism controlling said circuit, of a gate circuit including gate contacts, electromagnetic relay means in said gate circuit actuated on closing thereof for permitting closing of said operating circuit by said elevator starting mechanism, and a break relay for opening said gate circuit if said elevator starting mechanism is manipulated prior to closing 120 of said gate contacts.

5. In an elevator safety appliance, the combination with an elevator operating cir- 130

cuit, a line switch magnet and a starting switch for controlling said circuit, of a gate circuit, means actuated on closing said gate circuit followed by actuation of said starting switch for closing a circuit through said line switch magnet, and means for breaking said gate circuit if said starting switch is first closed.

6. In an elevator safety appliance, the combination with an elevator operating circuit, gate contacts, and an elevator starting mechanism including an "up" line switch magnet and a "down" line switch magnet, both magnets controlling said operating circuit, of means for determining whether or not said magnet shall control said operating circuit, said means requiring the closing of all gate contacts and manipulation of said elevator starting mechanism, means being provided whereby both line switch magnets are rendered ineffective to close said operating circuit if said elevator starting mechanism is manipulated prior to the closing of the gate contacts.

25 7. In an elevating safety appliance, the combination with an elevator starting switch, gate contacts and an elevator operating circuit, of relay means controlled by said switch and in series with said gate contacts for determining whether said switch shall control the closing of said operating circuit, a break relay for breaking the circuit through said relay means, the circuit for said break relay being closed by said elevator starting switch, and means controlled by said break relay for breaking the gate circuit if said starting switch is closed prior to said gate contacts.

8. In an elevator safety appliance, the combination with an elevator operating circuit, an "up" line switch magnet and a "down" line switch magnet for controlling said operating circuit, and a starting switch for said magnets, of a gate circuit, means actuated on closing said gate circuit for permitting said starting switch to energize either said "up" magnet or said "down" magnet, and means for breaking said gate circuit if said starting switch is first closed, thereby preventing energization of either line switch magnet.

9. In an elevator safety appliance, the combination with an elevator operating circuit, an "up" line switch magnet and a "down" line switch magnet, and a line switch circuit including said switch magnets in parallel, of a gate circuit including gate contacts, electromagnetic relay means in said gate circuit, and contact means in said line switch circuit closed by said relay means.

10. In an elevator safety appliance, the combination with an elevator operating circuit, an "up" line switch magnet, a "down" line switch magnet, and a line switch circuit

including said switch magnets in parallel; of a gate circuit including gate contacts, relay electromagnetic means in said gate circuit, contact means in said line switch circuit closed by said relay means, and an elevator starting switch for closing said line switch circuit through either line switch magnet.

11. In an elevator safety appliance, the combination with an elevator operating circuit, an "up" line switch magnet, a "down" line switch magnet, and a line switch circuit including said switch magnets in parallel; of a gate circuit including gate contacts, electromagnetic relay means in said gate circuit, contact means in said line switch circuit closed by said relay means, and an elevator starting switch for closing said line switch circuit through either line switch magnet, if said gate contacts are first closed, and means for breaking said gate circuit if said starting switch is moved to line switch circuit closing position prior to closing of said gate contacts.

12. In an elevator safety appliance, the combination with an elevator operating circuit and a starting switch, of a control circuit for said operating circuit, a gate circuit, gate contacts in said gate circuit, switching means in said control circuit normally open, switching means in said gate circuit normally closed, a break circuit, switching means in said break circuit normally closed, means operating on closing said gate contacts for opening the switching means in said break circuit and closing the switching means in said control circuit, and means for opening the switching means in said gate circuit if said starting switch is actuated to elevator starting position prior to closing of the gate contacts.

13. In an elevator safety appliance, the combination with an elevator operating circuit and a starting switch, of a control circuit for said operating circuit, a gate circuit, gate contacts in said gate circuit, switching means in said control circuit normally open, switching means in said gate circuit normally closed, a break circuit, switching means in said break circuit normally closed, electromagnetic relay means operating on closing said gate contacts for opening the switching means in said break circuit and closing the switching means in said control circuit, and break relay means for opening the switching means in said gate circuit if said starting switch is actuated to elevator starting position prior to closing of the gate contacts.

14. In an elevator safety appliance, the combination with an elevator operating circuit, an "up" line switch magnet and a "down" line switch magnet for closing said circuit, a line switch circuit including said line switch magnets in parallel and a starting switch for throwing either magnet

- in circuit, of a control circuit for said operating circuit, a gate circuit, gate contacts in said gate circuit, switching means in said control circuit, normally opened, switching means in said gate circuit normally closed, a break circuit, switching means in said break circuit normally closed, means operated on closing said gate contacts, and throwing said starting switch in either direction, for opening the switching means in said break circuit and closing the switching means in said control circuit, an electromagnetic break relay in said break circuit energized by throwing said starting switch to one position, a second electromagnetic break relay energized by throwing said switch to another position, means being provided whereby, when either break relay
- opens the switching means in said gate circuit, the control circuit is broken, thereby preventing said starting switch from energizing, either said "up" switch magnet or said "down" switch magnet. 20
15. In an elevator safety appliance, the combination with an elevator operating circuit, line wires therefor, a control circuit for said operating circuit, and a gate circuit for determining the opening and closing of said control circuit; of gate contacts in said gate circuit rendered ineffective to close said control circuit if said gate contacts are grounded with one only of either line wire. 25

Signed at New York city, New York,
this 10th day of June, 1920.

NEVILLE S. DICKINSON.

Certificate of Correction.

It is hereby certified that the State of incorporation of the assignee in Letters Patent No. 1,483,216, granted February 12, 1924, upon the application of Neville S. Dickinson, of Glen Ridge, New Jersey, for an improvement in "Elevator Sequence Safety Devices," was erroneously given as "New York," whereas said State should have been given as *New Jersey*, as shown by the records of assignments in this office; and that the said Letters Patent should be read with this correction therein that the same may conform to the record of the case in the Patent Office.

Signed and sealed this 1st day of April, A. D. 1924.

[SEAL.]

KARL FENNING,
Acting Commissioner of Patents.
